UNITED STATES PATENT OFFICE.

CARL A. RAHMEL, OF DEFIANCE, OHIO.

CLAMPING DEVICE.

1,186,682.

Specification of Letters Patent. Patented June 13, 1916.

Application filed June 23, 1914, Serial No. 846,774. Renewed November 6, 1915. Serial No. 60,168.

To all whom it may concern:

Be it known that I, CARL A. RAHMEL, a citizen of the United States, and a resident of Defiance, in the county of Defiance and State of Ohio, have invented certain new and useful Improvements in Clamping Devices, of which the following is a specification.

My invention relates to means for quickly clamping and unclamping material being worked in desired positions on wood and metal working machines, being shown in connection with a chain saw mortiser, and the main object thereof is to provide a clamp which securely holds the work but which, when desired, may be immediately unclamped to permit the work to be moved into other positions.

A further object is to provide a cam for actuating the clamping slide.

A further object is to provide a resilient clamping member when my device is used with wood working machinery, so as not to mar the work.

A further object is to provide an adjustable support for the clamp.

A further object is to provide an adjustable stop, whereby the work may be accurately positioned.

A further object is to provide means for normally holding said stop in operative position.

A further object is to provide a lever for making said stop inoperative, in order to move the work, and which lever is operable by the same hand of an operator used to release the clamp, thus leaving his other hand free to shift the work.

My invention is fully described in the following specification, of which the accompanying drawings form a part, in which the separate parts are designated by the same reference characters in each of the views, and in which:

Figure 1 is a perspective view of my invention in position for use on a chain saw mortising machine, in clamping position; Fig. 2 is an enlarged plan view thereof; Fig. 3 is a section taken on the line 3—3 of Fig. 2; Fig. 4 is a section taken on the line 4—4 of Fig. 2, showing the clamp in released position, and also the stop; and Fig.

5 is a fragmentary, front, elevation thereof, with the clamp in released position.

In the drawings forming a part of this application I have shown a wood working machine provided with the work table 10, and vertically movable chain-saw 11, and I arrange my invention on said table, adjacent the front edge thereof, said device comprising a base 12 having slots 13 therein through which are passed bolts 14 secured in the table 10, thus permitting the adjustment of the base 12 with respect to the table 10, and said base is provided with three uprights 15, 16 and 17, and through the two first of which passes a pivot pin 18 for a cam-disk 19 having a handle 20, and the inner sides of the uprights 15 and 16 are provided with beveled grooves 21 in inward projections 22.

Slidable between the uprights 15 and 16 is a bar 23 resting upon the projections 22 thereof and having a downwardly extended, beveled, key 24 sliding in the grooves 21, and said bar is provided with a segmental recess 25 within which the cam-disk 19 is arranged, and it will be seen that when the handle 20 is moved upwardly, from the clamping position shown in Fig. 3, to the position shown in Fig. 4, the bar 23 is forced outwardly and, in the reverse movement, inwardly.

Secured to the inner end of the bar 23 is a head 26 in which two dowels 27 are slidably arranged, said dowels being carried by a plate 28 which may be of any length and is adapted to bear upon the work, and I also provide rubber or other resilient sheets 29 between the head 26 and the plate 28 whereby a yielding pressure results against the work when clamped in position.

Rotatable in the uprights 16 and 17 is a rod 30 having a groove 31 for a portion of its length to position a set-screw 32 in a stop 33 for the work, said stop being formed approximately on a segment of a circle whereby the weight of the extending arm 34 will cause the same to fall out of operative position by gravity, but to maintain said stop in operative position I provide a spring 35 secured, at one end, to an eye in the upright 17 and at the other end to an arm 36 on the rod 30 and, to move said stop

against the action of its spring, I provide a lever 37, in detachable engagement with the rod 30, and adjacent the cam handle 20, and which may be grasped by the same hand of an operator used to move the handle 20, and both the clamp and stop be simultaneously moved into inoperative positions, but, when the lever 37 is released, the spring 35 again moves the stop into operative position, and, if the stop is not to be used, the spring may be detached and the stop falls into inoperative position, as already explained.

The work is placed upon the table 10, and the base 12 suitably adjusted and the handle 20 moved into operative position, at which time the machine may be actuated and, after such actuation, the clamp may be released with one hand and the other hand used to move the work into position for the next machine operation thereon, this clamping and releasing of the work being instantaneously performed, as will be seen. It will thus be seen that I provide a clamp which is readily attached to any machine, and adjustable thereon, and which also combines the advantages of a work stop therewith; which is simple in construction and operation; which is composed of but few parts not likely to get out of order to require repair; which is very strong; which is operable with one hand; and which is comparatively inexpensive.

While I have shown certain details of construction it will be obvious that I do not limit myself thereto, but may make changes therein and modifications thereof, within the scope of the following claims, without departing from the spirit of my invention or

Copies of this patent may be obtained for five cents each, by addressing the "Commissioner of Patents, Washington, D. C."

sacrificing its advantages and, with such reservation,

What I claim as new, and desire to secure by Letters Patent, is:—

1. The combination with a table for work having a rigid vertical member; of a clamp, comprising a base provided with a plurality of uprights, a bar slidably engaged between two of said uprights, a plate in resilient connection with the inner end of said bar, an adjustable stop carried by two of said uprights, means for actuating said bar, and means for actuating said stop, said actuating means being in approximate juxtaposition.

2. The combination with a table for work having a rigid vertical member; of a clamp, comprising a base provided with a plurality of uprights, a bar slidably between two thereof; a plate in resilient connection with the inner end of said bar, a rod supported by two of said uprights, a work stop slidably adjustable thereon, means for normally maintaining said stop in operative position, means for moving the same out of such position, and means for actuating said bar inwardly and outwardly, toward and from said vertical member, said bar actuating means and said stop moving means being in approximate juxtaposition, whereby both may be engaged by one hand of an operator.

In testimony whereof I have signed my name to this specification in the presence of the subscribing witnesses.

CARL A. RAHMEL.
